**METHOD OF STERILIZING WITH ALKYLENE
 OXIDE**
 Richard M. Donchak, Norwich, and Joseph J. May,

 Company, a corporation of New York
 No Drawing. Filed Nov. 16, 1961, Ser. No. 152,936
 4 Claims. (Cl. 167—58)

This invention relates to a sterile topical aerosol preparation and the process for preparing same. More particularly, this invention relates to self-sterilizing human topical aerosol preparations comprising 20 to 500 p.p.m. of an alkylene oxide which compound is introduced into a pressurized aerosol dispenser in admixture with a propellant such that the concentration of said alkylene oxide to said propellant is in the range of 40 to 1000 p.p.m. and preferably 40 to 400 p.p.m.

In the prior art, alkylene oxides have been used as sterilants and food preservatives. Alkylene oxides, however, have not been used successfully as a sterilant for topical pharmaceutical preparations because of their highly toxic nature. For example, exposure of human skin for about two hours to a 1% solution of ethylene oxide in water will cause second degree burns (Arch. Indus. Hyg. Occup. Med. 2: 549-564, November 1950).

It has now been found that minute non-toxic concentrations in the range of 20 to 500 p.p.m. and preferably 20 to 200 p.p.m. of alkylene oxide in combination with an inert gas will successfully destroy even the most resistant microorganisms if exposed over a period of 2 to 60 days. It has further been found that if the mixture of alkylene oxide and inert gas is combined with the material to be sterilized and held under a pressure of 15 to 100 p.s.i.g. that the time in which sterility is achieved is substantially reduced. These findings not only provide a more economical means of sterilizing topical pharmaceutical preparations packaged in the form of an aerosol spray, but also provide a means for sterilizing those preparations or formulations which are not stable at the high temperatures used in autoclaving. Another advantage of the present invention is the fact that adequate proportions of alkylene oxide are retained within the pressurized dispenser throughout its use to prevent any contamination of the contents.

The alkylene oxides useful in this invention are ethylene oxide and propylene oxide, particularly useful, however, is ethylene oxide which compound is considered the more active sterilant.

The alkylene oxides are preferably blended with an inert gaseous propellant such as carbon dioxide or nitrogen. Particularly useful, are the commercially available Freon and Genitron propellants such as monochlorodifluoroethane, trichloromonofluromethane and mixtures thereof. The alkylene oxide is mixed with the propellant by introducing 40 to 1000 p.p.m. of alkylene oxide into a charged or liquified cylinder of said propellant. Then the propellant-alkylene oxide mixture, normally in a liquid state, is introduced into the individual aerosol dispenser containing the topical pharmaceutical preparation and sealed therein under an internal pressure of 15 to 100 p.s.i.g. by conventional means. The alkylene oxide-propellant mixture will effectively sterilize the aerosol preparation in 2 to 60 days, the actual time for any particular preparation will be dependent upon the concentration of alkylene oxide and internal pressure of the aerosol dispenser. Even at minimum concentrations of about 20 p.p.m. complete sterilization can be expected within about 4 to 5 weeks under normal aerosol pressures of 15 to 100 p.s.i.g.

2

The following example is illustrative of the present invention:

Example I

5 A. To determine the effectiveness of minute non-toxic concentrations of ethylene oxide as a sterilant, a topical pharmaceutical preparation having the following formulation was prepared:

	Percent
Hexylene glycol	24.875
10 Polyethylene glycol	24.895
Furacin (5-nitro-2-furaldehyde semicarbazone)	.21
Trichloromonofluromethane	25.00
Monochlorodifluoroethane-ethylene oxide mixture	25.00

15 The aerosol units to be tested were inoculated with spores of *Bacillus subtilis*. Inoculum 5,625,000 cells/ml. of the above formulation. (Spore count was determined by plate dilution method using heart infusion agar and distilled water pH 5.7.) *Bacillus subtilis* spores were selected because of their known resistance to the antimicrobial agent—Furacin. After inoculation, the test units were filled with 1.25 oz. avoirdupois of the above glycol-Furacin solution then the 25% by weight of trichloromonofluromethane was added followed by addition of 25% by weight 25 of the monochlorodifluoroethane-ethylene oxide mixture. The monochlorodifluoroethane-ethylene oxide mixtures were prepared via a pressure burette such that the total concentration in the test units was varied from 500 to 0 p.p.m. The 0 p.p.m. being used as a control. Initial pressure within the test units was 18 p.s.i.g.

20 B. The above samples were tested for sterility at regular intervals by both the U.S.P. and the Millipore Filter Technique with the following results:

(1) *U.S.P. sterility test procedure*.—One second bursts 35 (0.5 ml.) of Furacin Solution Aerosol from the inoculated sample was sprayed directly into 200 ml. thioglycollate broth. Flasks were then incubated at 37° C. for 72 hours. Aerosol containers were stored at 25° C. throughout the experiment. All samples indicating growth were checked 40 by microscopic examination.

	Formulation	p.p.m. Ethylene Oxide	Weeks incubation @ 25° C. required to kill spores

60 Formulation A—as given above.

Formulation B—as given above but without .2% Furacin.

¹ Non-sterile—growth observed after 9 weeks' incubation at 25° C.

65 (2) To check the above results the test units containing 500; 100; 50 and 0 p.p.m. ethylene oxide (Formulation A) were tested after 9 weeks incubation at 25° C. for sterility by the Millipore Filter Technique. In this method, one cc. of the inoculated sample was sprayed into a Millipore filter and washed with one liter of sterile distilled water. In this way, the Furacin was washed through the filter leaving *B. subtilis* spores on the filter. The filter 70 was transferred to thioglycollate media and incubated for

72 hours at 37° C. and checked for sterility. The units containing 500, 100 and 50 p.p.m. ethylene oxide were sterile; the unit containing 0 p.p.m. ethylene oxide was non-sterile.

Example II

To further illustrate the present invention 1150 aerosol samples containing Formulation A were prepared under non-sterile commercial packaging conditions by first preparing and filling the sample units with 1.25 oz. avoirdupois of the 0.2% Furacin in hexylene glycol-polyethylene glycol base and then introducing the propellant (25% by weight of trichloromonofluoromethane was added followed by addition of 25% by weight of a monochlorodifluoromethane-ethylene oxide mixture) containing 70 p.p.m. ethylene oxide, such that the final concentration of ethylene oxide within the aerosol was 35 p.p.m.

A total of 30 samples were removed from this run (10 from the beginning 10 from the middle and 10 from the end) and checked for sterility by the Millipore Filter Technique. The samples were incubated at 37° C. and 55° C. for 10 days using Difco Fluid Thioglycollate media. All samples were found to be sterile after 10 days.

What is claimed is:

1. In the method of sterilizing with alkylene oxides is a substantially non-aqueous medium, the improvement by which human topical aerosol preparations are sterilized by protracted storage at room temperature which comprises charging said aerosol preparations under an internal pressure of 15 to 110 p.s.i.g. with a gaseous mixture of an inert gaseous propellant selected from the group consisting of carbon dioxide, nitrogen and halogenated lower alkyl hydrocarbons containing at least one fluorine atom and an alkylene oxide containing 2 to 3 carbon atoms,

such that the sterilizing concentration of the alkylene oxide in the aerosol preparation will be in the range of 20 to 500 p.p.m.; and storing said aerosol preparation under said pressure at room temperature for a period of 1 to 4 weeks.

2. The method according to claim 1 wherein said alkylene oxide is ethylene oxide.

3. The method according to claim 1 wherein said alkylene oxide constitutes 40-1000 p.p.m. of the gaseous mixture.

4. The method according to claim 1, wherein said alkylene oxide in the aerosol preparation is present in the range of 20 to 200 p.p.m. and said aerosol is stored at room temperature for a period of 2 to 4 weeks.
